Application October 4, 1952, Serial No. 313,148

3 Claims. (Cl. 37—103)

My invention relates to shoveling mechanisms, and more particularly to shoveling mechanisms which have special suitability for trenching operations, and which are adapted to remove material from below a surface upon which a vehicle supporting the shoveling mechanism is adapted to be supported, and to raise it to a hopper or the like on the vehicle, from which hopper the material is adapted to be discharged to trucks or other conveyances which may move it to a suitable point of disposition.

It is very frequently necessary to form trenches in paved streets in order either to lay pipes, conduits, cables or the like, or to secure access to such conductors which have already been placed in the ground and had paving laid over them. A desirable method of forming such trenches comprises as a first step the cutting of rather narrow parallel slots at an appropriate distance apart to form lateral boundaries of the trench to be dug. The slots should extend through the paving and should be of minimum practicable width because the cutting of the paving is a comparatively slow job. After the slots have been formed, so that a strip of paving has been severed, it is desirable to break it up into fragments of such size as to permit handling by a shovel. It may be broken either into pieces of substantial size or into fragments comparable to the various sizes of anthracite coal. After it has been fractured to handleable size, it is desirable to shovel it out, and to have the shoveling apparatus able to work sufficiently below the surface of the pavement completely to remove the layer of paving, and to raise the material which it handles high enough so that it can be dumped into a hopper and loaded out of the latter into trucks for transportation to a desired place of disposition.

It is desirable that the shoveling mechanism shall be simple and rugged, be vehicle-supportable, preferably be powered hydraulically, and be capable of performing its operations with controls which are as simple as possible.

An object of my invention is to provide an improved shoveling mechanism. Another object of the invention is to provide an improved shoveling mechanism particularly adapted for handling material from cuts in paving. A further object of the invention is to provide an improved hydraulically operated shoveling mechanism of high lift. Still another object of the invention is to provide an improved hydraulically operated shoveling mechanism having a minimum number of hydraulic cylinder and piston mechanisms for the execution of its necessary functions. Other objects and advantages of the invention will be apparent from the following description and appendent claims:

In the drawings:

Fig. 1 is a side elevational view with parts broken away showing one illustrative embodiment of the invention.

Figs. 2, 3 and 4 are fragmentary views showing the

shoveling mechanism of Fig. 1 in different operating positions.

Fig. 5 is an enlarged, fragmentary view, with parts broken away, similar to portions of Fig. 1.

Fig. 6 is a horizontal section on the planes of the line 6—6 of Fig. 5.

Fig. 7 is a bottom view, on the plane of the line 7—7 of Fig. 5, of the structure shown in the latter figure.

Fig. 8 is a vertical transverse section on the planes of the line 8—8 of Fig. 5.

Figs. 9 and 10 are respectively plan and side elevational views, on a further enlarged scale, showing the main shovel swinging frame and certain connected parts, separated from the rest of the apparatus.

Fig. 11 is a diagrammatic view showing the hydraulic system in its illustrative form.

Fig. 12 is a central longitudinal sectional view through a control valve box.

Referring now to the drawings, there will be noted at V, a vehicle of the self-propelled type. It has supported on it, as shown, a pressure fluid operated breaker mechanism 1. This vehicle supports the shoveling mechanism, which is generally designated 2. The vehicle also supports a hopper 3 into which the shoveling mechanism is adapted to deposit the material which it handles. 4 is a conveyor of any suitable construction which takes material out of the hopper 3 and delivers it to a transport vehicle which has been moved into position for the reception of a load. Desirably, the conveyor 4 is secured to the hopper 3 in such a manner that rotation of the hopper about a vertical axis may also result in repositioning of the conveyor. The hopper and conveyor can be rotated on the vertical axis mentioned, and for this purpose there may be utilized cable mechanism including a cable C which extends in a groove G about the base of the hopper, and which may have traction exerted on either of its opposite ends or be held stationary in any suitable manner and by any suitable means. This cable mechanism is illustrated only sufficiently to indicate its presence. As the hopper, conveyor, and their rotating means are but adjuncts of the shoveling mechanism which constitutes the present invention, no detailed illustration of their construction is required, this being true, moreover, because those skilled in the art of material handling will readily comprehend both satisfactory specific constructional features and mode of operation. The truck is supported on wheels W, and power may be delivered to all of these wheels or to either pair thereof from an engine (not shown) disposed beneath a hood H on the body of the vehicle V, in any well-known and conventional manner.

Much of the structure of the shoveling mechanism will be observed to be in effect duplicated at each side of the central longitudinal vertical plane of the bucket or shovel proper, but might be consolidated were it not simpler—to avoid interference of parts—to use the arrangement shown for specific illustration.

The vehicle V is provided, between the hopper 3 and the wheels W which are more remote from the hopper, with an open space S between its body frames F. Through this open space, the shovel is adapted to be swung upwardly and downwardly between loading and discharge position.

The vehicle frame includes laterally spaced, depending, longitudinally extending support portions P. At each side of the shoveling mechanism, there are shown two push-pull devices, herein in the form of hydraulic cylinder and piston mechanisms, 5 and 6. These are pivotally mounted, respectively at 7 and 8, on depending arm structures 9 and 10, rigid with the depending frame portions P.

and so rigid with the body of the vehicle V. Because of the duplication of construction mentioned, it is to be borne in mind that there are two cylinders 5, and two cylinders 6, and it is again to be noted that the mechanisms associated with these cylinder and piston mechanisms are at least mostly constructed as it were in duplicate, though at times the duplicated parts are integrally connected, and are operatively connected to the shovel in such a manner that the latter is supported and has forces transmitted to it at each of the opposite sides of its longitudinal central vertical plane.

A shovel, scoop or bucket is shown at 11. At its rear, it is provided with parallel, upright, rearwardly extending plate portions 11'. An armlike frame 12 comprises parallel side arm portions 13, 13 connected at their lower ends by a hollow cross brace 14 and nearer their other ends by a second hollow cross brace 14'. The lower ends of the arm portions 13, 13 and the cross brace 14 lie between the plate portions 11', and a pivot element 15 extends through the hollow cross brace 14 and the rearwardly extending plate portions 11' near the bottom of the shovel, and supports the latter on the frame 12. The other, opposite, ends of the arm portions 13, 13 are pivotally connected to the depending frame portions P as by a pivot shaft 16, which extends also through a tubular brace 17 connecting the depending frame portions P and which, furthermore, outside of strengthening and bearing-providing bosses 13', 13' formed at the ends of the arm portions 13, 13, provides pivotal supports for rocker members or rockers 18, 18.

The piston and cylinder mechanisms 5, 5 have piston rods 19, 19, and these are pivotally connected to the rockers 18, 18, at one end of the latter, at 20. The other ends of the rockers are pivotally connected at 22 to links 23, 23. The links 23, 23 are pivotally connected at 24, to at their other ends from the pivotal connections 22, to adjacent one corner of such plates. Each of these plates is pivotally connected at another corner thereof to a projection 27 on the arm portion 13, by means of a pivot shaft 26 extending through the hollow cross brace 14' on which extends between and connects projections 27 on said arm portions 13. Shaft 26 may desirably have the members 25 secured to it. The third corner of each plate 25 has pivotally connected to it at 28 a link 29, which is pivotally connected to the shovel 11, at a pivot point 30 above, in the lowered position of the shovel, the pivot element 15. The pivot points 30 are located at the mutually outer sides of the upright plate portions 11'. Each cylinder and piston mechanism 6 has a piston rod 31. Each piston rod 31 has a pair of pitman-like links 32 pivotally connected to it by pivot elements 33. The other ends of these pitman-like links are connected with a tubular body 34 which extends between further projections 35 formed on the arm portions 13, 13, and a pivot element 36 traverses the projections 35 and the tubular body 34. Links 37, connected at their upper ends by a hollow bar 38 which is pivoted at 39 on the frame portions P, are connected at their other ends, at 40, to the pivot elements 33.

The hydraulic control system for the cylinder and piston mechanisms 5 and 6 is illustrated in Fig. 11. It will be noted that fluid flow with respect to the cylinder and piston mechanisms 5, 5 is effected simultaneously with respect to each of them. This is also true of the cylinder and piston mechanisms 6, 6. The cylinder and piston mechanisms 5, 5 and 6, 6 are all double-acting. A pump O, desirably actuated by power from the power plant of the vehicle, takes fluid through a conduit 41 from a sump or tank T and discharges it to a pump discharge line 42 which leads to a valve box structure, generally designated 43. This valve box structure has a supply box 44 to which the pump discharge line 42 leads. A relief valve 45 is associated with the supply box 44, and fluid is released, when pump discharge pressure gets higher than

the setting of the relief valve 45, and is adapted to be returned through a connection 46 to the sump. The connection 46 communicates with a discharge box 47 in a well-known manner. Between supply box 44 and discharge box 47 are control valve boxes 48 and 49. The control valve box 48 controls the supply and venting of fluid to the opposite ends of the cylinder and piston mechanisms 5, 5. The control valve box 49 controls the supply and venting of fluid to the opposite ends of the cylinder and piston mechanisms 6, 6. The control valve boxes 48 and 49 are standard commercial products, as are also the supply box 44, the relief valve 45 and the discharge box 47. Their structure therefore really needs no illustration, and though some details will later be given, it will suffice for now to say that the control valve boxes 48 and 49 contain valves 50 and 51 indicated conventionally in dotted lines, and respectively operated by operating handles 52 and 53, and that in the central position of the valves 50, 51 fluid flows freely from the conduit 42 to the conduit 46, while the conduits connecting the valve boxes respectively with the cylinder and piston mechanisms 5, 5 and 6, 6 have their communication with the conduits 42 and 46 both interrupted. In other words, fluid is trapped in the cylinder and piston mechanisms 5, 5 and 6, 6 in the centered positions of their respective control valves 50 and 51. When the control valve 50 is in one end position, it may supply fluid to one end of both of the cylinder and piston mechanisms 5, 5 and vent the other ends thereof. In its opposite position, it supplies fluid to the second ends of the cylinder and piston mechanisms 5, 5 and vents the first ends. In one end position of the valve 51, it supplies fluid to the corresponding ends of both cylinder and piston mechanisms 6, 6, while venting the opposite ends. In its other end position, it supplies fluid to the last mentioned ends of both of these cylinder and piston mechanisms and vents the first mentioned ends thereof. Valve 51 cannot interrupt, by displacement to one of its end positions, the availability of fluid to the cylinder and piston mechanisms 5, 5, and the pump 40 has adequate capacity for the supply of fluid to the cylinder and piston mechanisms 5, 5 and 6, 6 simultaneously. One point in the valve box 48 is connected by a conduit 55 with a cross connection 56 leading to the rod ends of the cylinder and piston mechanisms 5, 5. A cross connection 57 between the head ends of the cylinder and piston mechanisms 5, 5 is connected by a conduit 58 with a spaced point in the valve box 48. A conduit 59 leads from one point in the valve box 49 to a cross connection 60 between the rod ends of the cylinder and piston mechanisms 6, 6. A cross connection 61 between the head ends of the cylinder and piston mechanisms 6, 6 is connected by a conduit 62 to another point in the valve box 49.

In Fig. 12, there is shown a central section through the valve box 48. It will be observed that a bore 70 is provided by this valve box. In it multi-spool valve 50 is reciprocable. This bore has communicating with it at its center an annular groove 72, which is connected with return conduit 46. At opposite sides of the groove 72, there are grooves 73 and 74. These are connected respectively with the conduits 55 and 58. Outside the grooves 73 and 74, there are supply grooves 75 and 76. One further groove 77 is shown, and this is connected also to the line 46. It will be noted that, in the central position of the valve 50, fluid flows from the groove 76 to the groove 77 and thereby the pump O is freed of any back pressure when there is no cylinder and piston mechanism connected with the discharge line 42. The grooves 75 and 76 are connected together by a conduit 78. The valve 50 has peripheral grooves 79, 80 and 81, groove 80 between the other two. Groove 80 selectively connects grooves 73 and 74 with groove 72. Groove 79 selectively connects groove 76 with groove 74 or groove 77. Groove 81 connects groove 75 with groove 73 when groove 74 is connected with groove 72 by groove 80. A precisely similar arrangement is present in the case of

the valve box 49, save that the connections of the grooves corresponding to the grooves 73 and 74 are to the conduits 59 and 62. When the handles 52 and 53 have push applied to them, they move the valve mechanism to the right in Fig. 12. Thus push on the handle 52 will result in the supplying of fluid to the conduit 58 and venting of the conduit 55, and push on the handle 53 will result in fluid supply to the conduit 62 and venting of the conduit 59. The fluid supply system in each valve box 48 and 49 is in communication with the conduit 42 through the supply box 44, and the exhaust grooves 72 of each box 48 and 49, and the grooves 77 of each box are in communication with the discharge box 47 and so to the return connection 46.

There remains to be supplied only a brief description of the mode of operation of the foregoing apparatus.

In Figs. 1 and 5, the shovel is shown in digging position. The parts are all rigidly held in the position shown by reason of the fact that hydraulic fluid is trapped in the head ends of the cylinder and piston mechanisms 5 and 6. The vehicle moves towards the left to fill the shovel. It may be noted that in this position of the parts the piston rods 19 of the cylinder and piston mechanisms 5 are at least substantially fully extended. The piston rods 31 of the cylinder and piston mechanisms 6 are shown in nearly fully retracted position. A slight further retraction would result in a slight additional lowering of the shovel.

After the shovel has taken as much of the material as it will conveniently hold, fluid is admitted to the rod ends of the cylinder and piston mechanisms 5 to cause the piston rods 19 to be pulled downwardly. This causes swinging of the rockers 18 about the stationary pivots 16, which in turn causes the links 23 to rock the members 25 about the axis of the pivot shaft 26, with the result that traction is applied to the links 29 and the shovel 11 is brought to the position of Fig. 2. That is, it is raised at its digging end so that there is less prospect of material falling from it.

The next step is to effect operation of the lifting mechanism. Fluid is supplied to the rear ends of the cylinder and piston mechanisms 6, which forces the piston rods 31 outwardly, the piston rods 19 being maintained at this time in retracted position. As a result of the outward movement of the piston rods 31, the links 32 force the frame 12 to swing upward. Meanwhile, the links 23, the members 25, and the links 29 regulate the angle of the bucket to the swinging frame 12 so that the bucket is maintained in load-carrying position as it is moving clockwise bodily with the arms 13, but turned counter-clockwise with respect to the frame 12.

When the parts reach the position of Fig. 3, fluid is supplied to the head ends of the cylinder and piston mechanisms 5, and this effects a rotation of the shovel 11 from the position of Fig. 3 to the dumping position shown in Fig. 4, during this operation the shovel 11 being swung sharply clockwise relative to the frame 12 about the pivotal connection 15.

To lower the bucket, fluid may be supplied simultaneously to the cylinder and piston mechanisms 5 and 6, to retract the piston rods 31, and to force the piston rods 19 outwardly in the cylinder and piston mechanisms 5. Obviously, there are two controls on the depth of digging, the cylinder and piston mechanisms 5 raising and lowering the digging edge of the shovel in a given position of the arm portions 13 of the frame 12, and the angle to the vertical of the frame 12 controlling the height of the pivot element 15 and thus providing an additional control of the depth of digging.

It will be evident that the apparatus described is simple and rugged, provides all necessary controls of the shovel, and is well adapted to the problems it was designed to meet.

While there is in this application specifically described one form which the invention may assume in practice, 75

it will be understood that this form of the same is shown for purposes of illustration and that the invention may be modified and embodied in various other forms without departing from its spirit or the scope of the appended claims.

What is claimed is:

1. A frame providing a horizontal transverse axis, a shovel, an arm structure pivotally connected at one end at said horizontal axis and at its other end pivotally connected to said shovel, a triangular plate pivoted at one corner thereof on said arm structure between the ends of the latter, a link connecting another corner of said triangular plate with said shovel at a point nearer the top of the latter than the connection of said arm structure with said shovel, a rocker having oppositely extending arms and rockable about said horizontal axis, a link pivotally connected at one end to said triangular plate at the third corner of the latter and at its other end to one of the arms of said rocker, a first cylinder and piston mechanism pivotally connected to said frame at a point on the latter on the other side of said horizontal axis from the pivotal connection of said arm structure to said shovel and to the other arm of said rocker, a link connected with said arm structure at a point on the latter nearer the pivotal connection of the latter with the frame than is the pivotal connection of said plate with said arm structure, a second cylinder and piston mechanism pivotally connected at one end to said frame at a point on the latter on the same side of said horizontal axis as the pivotal connection of said first cylinder and piston mechanism to said frame, and at its other end pivotally connected to said link last mentioned, means for controlling supply and venting of fluid with respect to said two cylinder and piston mechanisms, and means including a further link pivotally connected at one end to said frame and at its other end relative to said arm connected link for controlling movement of said latter link to cause said arm structure to undergo a swinging movement through an arc intersecting a plane through the longitudinal axis of said last cylinder and piston mechanism.

2. A frame providing a horizontal transverse axis, a shovel, an arm structure pivotally connected at one end at said horizontal axis to said frame and at its other end pivotally connected to said shovel, a member pivotally connected at one point thereon to said arm structure between the ends of the latter, a link connecting a spaced point on said member with said shovel at a point nearer the top of the latter than the connection of said arm structure with said shovel, a rocker having oppositely extending arms and rockable about said horizontal axis, a link pivotally connected at one end to said member at a third point on the latter and at its other end to one of the arms of said rocker, a first push-pull device pivotally connected to said frame at a point on the latter on the other side of said horizontal axis from the pivotal connection of said arm structure to said shovel and to the other arm of said rocker, a link connected with said arm structure at a point on the latter nearer the pivotal connection of the latter with the frame than is the pivotal connection of said member with said arm structure, a second push-pull device pivotally connected at one end to said frame at a point on the latter on the same side of said horizontal axis as the pivotal connection of said first cylinder and piston mechanism to said frame and at its other end pivotally connected to said link last mentioned, means for controlling said push-pull devices independently, and means including a further link pivotally mounted at one end relative to said frame and at its other end to said arm connected link for positioning the latter to control the swinging movement of said arm structure between generally vertical depending and generally vertical upstanding positions.

3. A frame providing a horizontal transverse axis, a shovel, an arm structure pivotally connected at one end at said horizontal axis to said frame and at its other end

pivots connected to said shovel, a member pivots connected at one point thereon to said arm structure between the ends of the latter, a link connecting a spaced point on said member with said shovel at a point nearer the top of the latter than the connection of said arm structure with said shovel, a rocker having oppositely extending arms and rockable about said horizontal axis, a link pivots connected at one end to said member at a third point on the latter and at its other end to one of the arms of said rocker, a first cylinder and piston mechanism pivots connected to said frame at a point on the latter on the other side of said horizontal axis from the pivotal connection of said arm structure to said shovel and to the other arm of said rocker, a link connected with said arm structure at a point on the latter nearer the pivotal connection of the latter with the frame than is the pivotal connection of said member with said arm structure, a second cylinder and piston mechanism pivots connected at one end to said frame at a point on the latter on the same side of said horizontal axis as the connection of said first cylinder and piston mechanism to said

frame, and at its other end pivots connected to said link last mentioned, means for controlling supply and venting of fluid with respect to said two cylinder and piston mechanisms, and means including a further link pivots mounted at one end to said frame and at its other end to said arm connected link and to said second cylinder and piston mechanism at the pivotal connection of the latter to control the swinging movement of said arm structure between a generally vertical depending and generally vertical upstanding position.
